CLUTCH FOR WINDOW REGULATORS

John H. Roethel, Detroit, Mich., assignor to Ferro Stamping and Manufacturing Company, Detroit, Mich., a corporation of Michigan

Application July 6, 1936, Serial No. 89,086

6 Claims. (Cl. 192—3)

This invention relates to clutch mechanisms adapted particularly, although not exclusively, for association with the window regulator mechanism for operating a vehicle window.

5 An object of the invention is to provide a friction clutch mechanism for a window regulator or the like, said mechanism being of simplified construction, relatively economical to manufacture and easy to assemble in production.

10 A further object of the invention is to provide a window regulator clutch of the type having interconnected driving and driven elements arranged within a casing and a torsion clutch spring interposed between said elements and the 15 casing, and wherein said elements are provided with means effective to maintain the spring in proper position against displacement during assembly and use of the device.

Another object of the invention is to provide 20 an improved clutch mechanism in which the parts thereof are so constructed and arranged as to permit the rotation of the driving element about an axis located at an angle to the axis of rotation of the driven element.

25 The above and other objects and advantages of the invention will appear from the following description and appended claims when considered in connection with the accompanying drawing forming a part of this specification.

30 In said drawing:

Fig. 1 is an edge view, partly in section, of window regulator mechanism embodying one form of the present invention.

Fig. 2 is a vertical section, on an enlarged scale, 35 of the regulator mechanism and clutch mechanism of Fig. 1.

Fig. 3 is a vertical section taken substantially along the line 3—3 of Fig. 2, looking in the direction of the arrows.

40 Fig. 4 is a vertical section taken substantially along the line 4—4 of Fig. 2, looking in the direction of the arrows; and

Fig. 5 is a perspective view, on a slightly reduced scale, showing the parts of the clutch mechanism of the present invention in disassembled relation.

Before explaining in detail the present invention it is to be understood that the invention is not limited in its application to the details of 50 construction and arrangement of parts illustrated in the accompanying drawing, since the invention is capable of other embodiments and of being practiced or carried out in various ways. Also it is to be understood that the phraseology or terminology employed herein is for the purpose 55

of description and not of limitation, and it is not intended to limit the invention claimed herein beyond the requirements of the prior art.

Referring now particularly to the drawing, I have shown one form of clutch mechanism embodying the present invention which is adapted particularly, although not exclusively, for use upon a mounting plate which is supported at an angle to the vertical, so that the operating handle located on the inner face of the door can be 10 rotated or turned in a vertical plane and thus not engage the inner face of the door.

In the present embodiment of the invention the clutch and regulator mechanism are shown mounted upon an inclined mounting plate 40, one 15 of the regulator mechanism gears or segments being shown at 41 and being provided with a swinging regulator arm 38. In the present form, the angular relationship of the regulator mechanism and mounting plate and the inner trim 20 panel 39 are best shown in Fig. 1. The gears 41, one only being shown, are adapted to be driven by means of a pinion 42 mounted upon a fixed short shaft or pin 43 carried by the offset portion 40a of the mounting plate 40, the pinion 25 being formed as a fixed part of the driven member of the clutch mechanism, as hereinafter described. Referring now particularly to the clutch mechanism, such mechanism comprises a cup-like driving member 44 having a pair of 30 outturned lugs or tongues 45. This member is rigidly mounted upon the inner end of a drive shaft 46 having a square outer end portion 47. The inner portion of the drive shaft 46 is drilled to receive with a press or driving fit a pin 48 35 which is provided with a spacer member 49. The pin 48 is adapted to receive and support the hub portion 51 of an intermediate clutch member or spider 50 having inturned flanged segmental portions 52 between which are located segmental 40 cut-out portions or notches 53. The driving member 44 is provided in its base with a square cut hole to receive a squared portion of the shank of the drive shaft 46. The parts are locked together by means of a rib 46a engaging one face 45 of the driving member and by upsetting or peening the metal of the squared shank at 46b at the other face of the driving member.

The driven member of the clutch mechanism is shown as a whole at 55 and comprises a disk-like body portion having inturned lugs or tongues 56 the inner portions of which are reduced in width at 57, see particularly Fig. 5. The driven member 55 carries the pinion 42 which is secured thereto in any suitable manner, so as to provide, 55

in effect, an integral unit. The inner face of the driven member 55 is provided with a ball or semi-spherical projection 58 which is adapted to fit within a correspondingly shaped socket portion or recess 59 in the outer face of the intermediate clutch member 50 (see particularly Fig. 2).

When the parts are assembled, the outer edges of the lugs or tongues 45 of the driving member engage the inner faces of the segmental portions 52 of the intermediate clutch member, with the pin end 48 fitting within the hub 51 and the hub in engagement with the stop or spacer 49. The driven member 55 has its ball-like portion 58 fitting within the socket 59 of the intermediate member and the lugs or inturned tongues 56, 57 of the driven member engage in the notches 53 and have a slight relative oscillating movement within the notches. The tongues 56, 57 have a similar relatively moving fit in the spaces between the outturned lugs or tongues 45 of the driving member. The clutch mechanism also includes a spiral torsion spring 60 of the expandable and contractible type, the spring having inturned end portions 61. The entire clutch mechanism with the exception of a portion of the driven member 55 and its supported pinion 42 is housed or located within a clutch housing or casing 62 having an angularly disposed marginal flange 63 which is attached to the inner face of the mounting plate 40 and preferably secured thereto by screws or rivets 64. It will be seen in Fig. 2 that the flange 63 is so shaped as to lie flat against the face of the mounting plate and yet the body portion of the casing or housing 62 is disposed so as to cause the shaft 47 to extend horizontally. A crank handle 65 is adapted to be removably applied to the squared end 47 of the drive shaft.

In the assembly of the clutch elements, as illustrated in Figs. 2, 3 and 4, the driving clutch member 44, the driven clutch member 55 and the intermediate clutch member 50 interfit and are substantially enclosed within the cup-shaped clutch housing 62. As will be seen, the outturned lugs or tongues 45 engage the inner face of the intermediate member and the inturned lugs or tongues 56, 57 of the driven member 55 are located within the spaces between the lugs 45 with the ball member 58 seated within the socket 59. The segmental lugs or projecting members 45 and 56 of the driving and driven members, respectively, have the same diameter and surrounding the same and located between the base of the driving member and the inner face of the intermediate member is the spiral torsion spring 60. When assembled this spring is interposed between the parts 45 and 56 and the cylindrical wall of the clutch housing 62. The side edges of the members 45 and 56 are in position to engage, respectively, opposite sides of the inturned ends 61 of the spring, as seen in Figs. 3 and 4. After the clutch members 44, 50 and 55, together with the spring 60, have been assembled within the clutch casing, the entire assembly is positioned upon the face of the mounting plate 40 overlying the offset portion 40a thereof. The unit comprising the driven member and the pinion is slipped over the stud or shaft 43 carried by the mounting plate offset portion 40a, after which the screws or bolts 64 are applied to secure the clutch housing to the mounting plate. With the parts in this position, the tongues or members 51 project through the notches 53 of the intermediate clutch member and extend into the spaces between the tongues 45 of the driving member. When the crank handle 65 is rotated in either

direction one of the offset ends 61 of the spring will be engaged by one of the tongues 45 to contract the spring and release it from binding engagement with the clutch casing, at which time the pinion 42 is driven through the engagement of the tongues 45 and 56. It is impossible for the regulator mechanism to be operated independently of the handle 65 since if an attempt is made to rotate the pinion in either direction an edge of one of the tongue members 56 of the driven element will engage the outside of one of the ends 61 of the spring and expand the spring outwardly against the inner wall of the clutch housing and thus lock the parts against rotation. By reason of the ball and socket connection 58, 59, between the driven and intermediate clutch members, the drive shaft 47 is located in a horizontal plane regardless of the angle of inclination of the mounting plate 40. Hence, as clearly seen in Fig. 2, the driven member 55 may be supported at the desired angle to the driving member 44, in order to accommodate the inclination of the mounting plate.

I claim:

1. A clutch mechanism for a window regulator comprising a housing, a driving clutch member, a driven clutch member, a gear operated by said driven clutch member, a torsion clutch spring interposed between said members and housing, and a ball and socket connection between the driving and driven members to permit said driven member to be positioned for rotation about an axis at an angle to the axis of rotation of said driving member.

2. A clutch mechanism for a window regulator comprising a housing, a driving clutch member, a driven clutch member, a gear operated by said driven clutch member, and a torsion clutch spring interposed between said members and housing and adapted to be expanded or contracted upon rotative movement of one member or the other, and an articulatable connection between said members to permit operative positioning thereof out of axial alignment.

3. A clutch mechanism comprising a housing, a driving clutch member, a driven clutch member, a gear associated with and operated by said driven clutch member, a spiral torsion spring interposed between the driven clutch member and said housing, and a ball and socket providing a limited universal connection between the driving and driven members to permit said driven member to be positioned for rotation about an axis at an angle to the axis of rotation of said driving member.

4. A clutch mechanism for a window regulator comprising a housing, a driving clutch member, a driven clutch member, a gear operated by said driven clutch member, an intermediate clutch member interposed between and engaging said driving and driven clutch members, a spiral torsion spring interposed between the driven clutch member and the housing, and a ball and socket connection between certain of said clutch members to permit said driven member to be positioned for rotation about an axis disposed at an angle to the axis of rotation of said driving member.

5. A clutch mechanism for a window regulator adapted to be supported upon an inclined mounting plate, comprising a casing, a driving clutch member having a pair of opposed segmental tongues, a driven clutch member having a pair of opposed segmental tongues, a gear mounted upon the outer face of said driven

member, an intermediate clutch member interposed between said driving and driven clutch members, friction clutch means interposed between the driven member and casing, and a limited universal joint connection between certain of said clutch members to permit said driven member to be positioned for rotation about an axis at an angle to the axis of rotation of said driving member.

5 10 15 6. A clutch mechanism for a window regulator adapted to be supported upon an inclined mounting plate, comprising a casing, a driving and a driven clutch member having interengaging parts, a gear mounted upon the outer face of said driven member, a handle shaft connected

to the driving clutch member, an intermediate clutch member interposed between said driving and driven clutch members, friction clutch means interposed between the members and casing, said intermediate clutch member having a socket formed in its outer face, and a semi-spherical projection formed on the inner face of said driven clutch member engaging said socket whereby to provide a limited universal connection between the driving and driven members to permit said driven member to be mounted upon said inclined mounting plate for rotation about an axis located at an angle to the axis of rotation of said driving member.
